UNITED STATES PATENT OFFICE.

JOHN H. CRITES, OF PONCA CITY, OKLAHOMA.

DESIGN FOR A BILLIARD CABINET OR SIMILAR ARTICLE.

Application filed September 17, 1927. Serial No. 23,449. Term of patent 14 years.

To all whom it may concern:

Be it known that I, JOHN H. CRITES, a citizen of the United States, residing at Ponca City, in the county of Kay and State of Oklahoma, have invented a new, original, and ornamental Design for a Billiard Cabinet or Similar Article, of which the following is a specification, reference being had to the accompanying drawing, forming part thereof.

The view is a perspective view of a billiard cabinet or similar article, embodying my design.

I claim:

The ornamental design for a billiard cabinet or similar article, as shown.

JOHN H. CRITES.
